(57) **CLAIM**

The ornamental design for a water container for beer brewing machine, as shown and described.

DESCRIPTION

1. Water container for beer brewing machine

1.2 : Front

1.3 : Back

1.4 : Left

1.5 : Right

1.6 : Top

1.7 : Bottom

1.8 : Reference view in the opened state

1.9 : Reference View in the disassembled state

1 Claim, 9 Drawing Sheets
